US00D596024S

(12) **United States Design Patent**
Fraguada McCoy et al.

(10) **Patent No.:** **US D596,024 S**
(45) **Date of Patent:** **** Jul. 14, 2009**

(54) **CONTAINER**

(75) Inventors: **Karla Marie Fraguada McCoy**, San Juan, PR (US); **Joseph Giaccone**, Ridgefield, CT (US)

(73) Assignee: **Kraft Foods Global Brands LLC**, Northfield, IL (US)

(**) Term: **14 Years**

(21) Appl. No.: **29/317,849**

(22) Filed: **May 8, 2008**

(51) **LOC (9) Cl.** **09-03**

(52) **U.S. Cl.** **D9/428**

(58) **Field of Classification Search** ..... D9/414–418, D9/424–432, 440, 445, 447, 449–450, 453–454, D9/500–504, 529, 549, 556–559, 562, 711, D9/772, 780; D7/602, 612–615, 629, 703; D6/632, 634, 407; D3/201, 203.2–203.4, D3/215, 265, 294, 302, 318, 904; D28/82, D28/91.1; 220/4.22–4.23, 23.88, 254.3, 220/254.7, 281, 283, 324, 376, 623, 796, 220/833, 835, 837–839, 8, 44, DIG. 26; 229/4.5, 229/5.5, 5.6, 5.84, 5.7, 406; 206/301, 536, 206/540; 131/242; 132/305

See application file for complete search history.

(57) **CLAIM**

The ornamental design for a container, as shown and described.

DESCRIPTION

FIG. 1 is a front elevational view of a container showing our new design, wherein the rear elevational view is a mirror image thereof.

FIG. 2 is a right side view thereof, wherein the left side view is a mirror image thereof.

FIG. 3 is a top plan view thereof; and,

FIG. 4 is a bottom plan view thereof.

The broken lines illustrate the boundary of the claim and form no part of the claimed design.
